ROTARY STAND FOR SEWING ACCESSORIES

William D. Taylor, Wooster, Ohio, assignor to Rubbermaid Incorporated, Wooster, Ohio, a corporation of Ohio

Filed Nov. 6, 1967, Ser. No. 9,297

Term of patent 14 years

(Cl. D3—19)

FIG. 1

Des. 212,071

PAGE 2

FIG. 2

FIG. 3

BY

FIG. 4

FIG. 1 is a perspective view of a rotary stand for sewing accessories embodying my new design.

FIG. 2 is a top plan view thereof.

FIG. 3 is a side elevation thereof.

FIG. 4 is a plan sectional view on line 4—4 of FIG. 3.

I claim:

The ornamental design for a rotary stand for sewing accessories, as shown.
